UNITED STATES PATENT OFFICE.

ADOLPH SCHNEIDER, OF CHICAGO, ILLINOIS.

FILLING-VALVE.

SPECIFICATION forming part of Letters Patent No. 728,307, dated May 19, 1903.

Application filed March 26, 1902. Serial No. 100,014. (No model.)

To all whom it may concern:

Be it known that I, ADOLPH SCHNEIDER, a citizen of the United States, residing at Chicago, in the county of Cook and State of Illinois, have invented certain new and useful Improvements in Filling-Valves, of which the following is a specification.

The object of this invention is to construct a valve especially adapted for use in the bottling of liquids under pressure and in which the bottling operation is performed under the conditions of equal pressure in the receptacle from which the liquid is drawn and in the bottle, for the equal pressure to act and prevent the foaming of the liquid in the bottling operation, and also insuring against deterioration of the liquid or loss in the bottling operation. The valve for use in filling the bottles under an equal pressure must have the capability of venting pressure into the bottle equal to the pressure in the liquid-receptacle prior to the admission of liquid into the bottle, and with the admission of liquid into the bottle the pressure is to be coincidentally forced out as the liquid enters and fills the bottle.

The primary object of the present invention is to construct a simple, effective, and reliable valve practically adapted for use with filling-machines for filling bottles with a liquid under pressure which will enable the pressure to be admitted to the bottle before the admission of the liquid; to improve the construction of the valve as regards the retention of the valve-plug within the valve casing or shell; to separate the liquid-passage and the pressure-passage, so as to give the liquid and the pressure separate lines of travel in entering into and passing out through the valve; to improve the construction, arrangement, and location of the filling-tube in its relation to the filling-plug and the passages in the plug for the liquid and pressure, and to simplify and improve the construction and operation of the constituent elements which enter into the construction of the valve and the filling-tube cooperating with the valve.

The invention consists in the features of construction and combinations of parts hereinafter described and claimed.

50 In the drawings, Figure 1 is an end elevation showing the preferred form of construc-

tion for the valve as a whole; Fig. 2, a side elevation of the construction shown in Fig. 1; Fig. 3, an end elevation showing a modification in the formation of the casing or shell carrying the valve-plug; Fig. 4, a side elevation showing a construction on the general plan of the construction of Figs. 1 and 2, but having a fixed plug instead of a fixed casing or shell; Fig. 5, a longitudinal section of the construction shown in Figs. 1 and 2; Fig. 6, a cross-section on line 6 of Fig. 5 looking in the direction of the arrow, with the filling-tube removed; Fig. 7, a cross-section on line 7 of Fig. 5 looking in the direction of the arrow, with the entered end of the filling-tube into the plug-valve in section and with the filling-tube (not shown) below the closing-cap; Fig. 8, a plan sectional view of the casing or shell for the plug-valve, showing the ports or openings in the casing or shell in full lines and the passages in the plug-valve in dotted lines in the position they occupy with the initial establishment of communication for the pressure to enter the bottle and the liquid port and passage closed against admission of liquid; and Fig. 9, a cross-section similar to Fig. 6 of the construction shown in Fig. 3.

The construction of valve of Figs. 1 and 2 has a casing or shell A, with a tapered interior chamber or opening for the reception of a plug-valve. The chamber of the casing or shell at one end is closed by a cap or head B and at the other end is closed by a cap or head B'. The shell or casing at one end has a projecting rim a with an interior screw-thread, into which is screw-threaded the closing cap or head B, and the cap or head B' at the terminus of its screw-threaded body has a flange b, which when the plug is fully entered abuts tightly against the end face of the rim a, making a close tight joint. The opposite end of the shell or casing has a rim a' with an interior screw-thread, into which is screw-threaded the closing cap or head B', and the cap or head, adjacent to its screw-threaded body, has a flange b', which when the cap or head is fully entered abuts against the end face of the rim a', making a close tight joint, and, as shown, each cap or head has in its outer face a slot or recess b² for the

reception of a screw-driver or other suitable instrument by means of which the caps or heads may be entered fully into place.

The casing or shell A has located in its chamber a controlling-valve D for the liquid and pressure, which valve, as shown, is in the form of a tapered plug fitting the correspondingly-tapered chamber of the casing or shell. The length of the plug-valve is less than the full length of the chamber therefore in the casing or shell, leaving a space in the arrangement shown between the face of the wide end of the valve and the closing cap or head B, in which is located a pressure-spring C, which spring exerts a sufficient force to hold the valve pressed inwardly with the requisite frictional contact between the walls of the plug-valve and the chamber of the casing or shell for holding the valve and the filling-tube against the filling-tube falling back when the valve is turned to shut off the passage therethrough of the liquid and pressure, and the spring also serves the purpose of holding the plug in its chamber, so as to maintain a close fit for the valve in its chamber, making a tight joint against leakage. The plug-valve has transversely therethrough a hole or passage, which, as shown, is circular in cross-section and of different diameters between its ends. The smallest end of the hole or passage transversely through the valve forms a port or opening d, and the section d' of the hole or passage adjacent to the port or opening d is screw-threaded to receive the end of the filling-tube, and the opposite end d² of the hole or passage to the port or opening d is of the greatest diameter and has a screw-thread for the attaching of the closing-cap on the filling-tube. The filling-tube E at its inner end is screw-threaded and entered into the hole or passage of the plug-valve, the screw-threads on the filling-tube end engaging the screw-threads of the section d' of the hole or passage, and when in place the hole of the filling-tube will be in alinement with the port or passage d in the plug-valve, as shown in Figs. 5 and 7. The filling-tube is of a length so that when inserted in a bottle it will extend down therein a sufficient distance for the filling operation, and, as shown, the extreme end of the filling-tube has on one or more sides a discharge port or opening e, which when the end of the filling-tube is in the neck of the bottle allows the liquid to discharge into the bottle. The filling-tube, as shown, has in its interior a vent-pipe F, which at one end is in communication with a port or opening f through the wall of the filling-tube and at its other end is in communication with a port or opening f' in the wall of the filling-tube, and this pipe also serves the purpose of a pressure-supply pipe for admitting a pressure corresponding to the pressure in the filling-tank into the bottle before supplying liquid to fill the bottle. The body of the filling-tube above the port or opening f is encircled by a closing-cap G,

which has a neck G' with an exterior screw-thread to enter the screw-threaded section d² of the hole or passage through the plug-valve, 70 and the neck G' passes through an elongated slot or opening g' in the casing or shell of the valve, which opening is of sufficient length to allow of the necessary turning of the plug-valve to shut off and admit liquid and pressure to pass through the valve. The closing-cap, as shown, is of a semicircular shape and at its outer open end has an inwardly-extending ledge or flange g, against which rests the lower edge face of a packing or cushion H, of 80 rubber or other suitable material, and, as shown, the packing or cushion has a central conical depending closure or stopper h, which when the filling-tube is in the neck of the bottle enters the mouth of the bottle and in connection with the packing or cushion H tightly closes the mouth of the bottle against the escape of liquid and pressure when the neck of the bottle at its end is held against the packing or cushion H of the closing-cap. 90

The plug-valve has an annular or circular passage or chamber c encircling the body of the filling-tube and into which the port or opening f' of the vent and pressure-supply tube opens. The casing or shell A on its upper side in the construction shown in Figs. 1, 2, 4, 5, 6, and 7 has a rim or wall I, through which and into the body of the casing or shell is a passage i, which terminates in a port i', with which the discharge-passage of the plug 95 can be brought into alinement for admitting the liquid to enter the filling-tube and be discharged therefrom. The wall or rim I, as shown, has an interior screw-thread for the reception of a coupling j on the end of a supply pipe or hose J, leading to the source of liquid-supply. The plug-valve has therein a passage k, which is in communication at its inner end with the annular passage or chamber c around the body of the filling-tube, and the receiving end or mouth k' of the passage k is elongated transversely of the valve. The receiving end or mouth k', when the plug-valve is properly turned, is in communication with a discharge end or mouth k² of a 105 passage k³ in the top wall of the casing or shell, and this discharge end or mouth k² is elongated transversely to correspond with the elongation of the receiving end or mouth of the passage in the plug-valve. The passage 110 k³ in the arrangement shown has entered thereinto a short pipe or tube K, and connected with the tube or pipe K by a suitable coupling l is a pipe or hose L, leading to the source of pressure in the filling-tank or otherwise. 115

The elongated receiving end or mouth k' and the elongated discharge end or mouth k², as to the length of space covered by the two, have a greater length than the space covered 120 by the ports or openings d and i', as shown by the dotted line in Fig. 8, and the elongated mouths are so located and arranged in relation to the ports or passages d and i' as that 125

with the turning of the plug-valve in the proper direction the passages k and k^3 and the ports or openings d and i' are closed against the admission of pressure and against the passage of liquid; but with the turning of the plug-valve in the direction for filling the bottle the initial movement in turning the plug-valve will open the passages k and k^3 by reason of the elongated mouths k' and k^3 allowing pressure to flow into the bottle before the admission of the liquid, with the result of placing the bottle under a pressure corresponding to that of the pressure on the liquid. The further turning of the valve into position for the filling fully opens both the passages k and k^3 for the admission of pressure and the passages d and i' for the admission of liquid, so that the liquid will enter the bottle under the same pressure as the pressure on the liquid, thus insuring the bottling of the liquid under an equal pressure in the bottle, thereby preventing any foaming in filling the bottle and insuring the bottling of the liquid without waste and deterioration.

The liquid flows from the filling-tank through the pipe or hose J , and with the ports or passages d and i' in line the liquid will flow through the filling-tube and be discharged therefrom at the port or opening e into the bottle, and with the filling of the bottle as the liquid rises therein the pressure will be expelled, passing out through the vent-tube F into the circular or annular passage or chamber c and through the passages k and k^3 into the pipe or hose L back to the source of supply, which may be the filling-tank. The bottle when filled, together with the filling-tube, is swung out of the filling position, and the movement in so doing turns the plug-valve to close the fluid passages and ports and the vent. It will be seen that the initial movement opens the vent and pressure passages for equalizing the pressure and the full movement to a filling position, for the filling-tube opens the liquid-passages and the vent and pressure-passages, with the result that the liquid entering by a gravity flow will force out the pressure in the bottle, making the filling operation one under the condition of equal pressure in the tank and bottle.

The construction in Figs. 3 and 9 instead of having a small wall or rim for the attachment of the liquid-supply pipe or hose has a neck I' with an exterior screw-thread for attaching the valve by a coupling to a filling-tank, the neck and the wall of the shell or casing having therein the passage i and port i' and the passage k^3 for the attachment of the coupling pipe or tube K , as in the construction of Figs. 1 and 2. The shell or casing A' in the form shown in Figs. 3 and 9 has a projection or extension a^2 on its rear face for the attachment of a bottle-support. (Not shown.) The valve of Figs. 3 and 9, with the exception of the shell or casing and the neck with the exterior screw-thread, is of the same

construction so far as concerns the form of the plug and the liquid-passages and the vent and pressure-supply passages in the same as described for the construction of valve of Figs. 1, 2, 5, 6, and 7.

The benefits and advantages of a valve having the liquid-passages and the vent and pressure-supply passages can be obtained by having the plug-valve held in a fixed relation and the casing or shell movable thereon, and a construction of this nature is shown in Fig. 4. The casing or shell A^2 is of the same general construction and arrangement as the casing or shell of Figs. 1 and 2 except that the casing or shell A^2 has thereon a handle a^3 , by which the casing or shell can be turned to bring the passages in coacting relation. The plug-valve D' is entered into its chamber in the casing or shell and at one end has a square projection b^3 and its other end has a square projection with a threaded stem b^4 extending out therefrom. The square extensions of the plug-valve are entered into correspondingly-shaped recesses or openings therefor in depending arms or bars M , each bar having a turned end m for fixedly attaching the arms in position to a support by bolts or otherwise. The stem b^4 is screw-threaded and has thereon a nut b^5 , which abuts against a washer b^6 , by means of which nut the plug-valve is drawn into the chamber, so as to make a tight fit and provide a close joint against leakage. The operation is essentially the same as described for the construction of Figs. 1 and 2, except that the casing or shell is turned to bring the liquid-passages and the vent and pressure-supply passages into communication and carry these passages out of communication with the same result so far as supplying an equal pressure between the filling-tank and the bottle to be filled as the result attained in the construction of Figs. 1 and 2. The filling-tube, with its closing-cap, is always in the same position by reason of its fixed connection to the plug-valve, which is non-turnable, and the casing or shell is the element by which the necessary communication is established and cut off for the liquid-passages and the vent and pressure-supply passages.

What I regard as new, and desire to secure by Letters Patent, is—

1. In a filling-valve, the combination of a casing or shell having therein a tapered chamber, a tapered plug-valve entered into the chamber of the casing or shell, a liquid-passage in the casing or shell, a liquid-passage extending transversely through the plug-valve in line with the liquid-passage in the casing or shell, a pressure-supply passage in the casing or shell having an elongated mouth, and a vent and pressure-supply passage in the plug-valve having an elongated mouth, each mouth of each passage elongated in the direction circumferentially of the plug for the elongations of the mouth to coact and open

the vent and pressure passages before the opening of the liquid-passages, substantially as described.

2. In a filling-valve, the combination of a casing or shell having therein a tapered chamber, a tapered plug-valve entered into the chamber of the casing or shell, a liquid-passage in the casing or shell, a liquid-passage in the plug-valve adapted to be brought into communication with the liquid-passage in the casing or shell, a filling-tube carried by the plug-valve in line with the liquid-passage of the valve, a vent and pressure-supply tube in the filling-tube, an annular or circular passage in the plug-valve in communication with the vent and pressure-supply tube of the filling-tube, a vent and pressure-supply passage in communication with the circular or annular passage of the plug-valve and having an elongated mouth, and a vent and pressure-supply passage in the casing or shell having an elongated mouth and with which the vent and pressure passage of the plug-valve is adapted to be brought into communication, for admitting pressure before admitting liquid through the valve, substantially as described.

3. In a filling-valve, the combination of a casing or shell, a controlling-plug entered into the casing or shell, a liquid-passage in the casing or shell, a liquid-passage in the plug extending transversely therethrough and in line with the liquid-passage in the casing or shell, a vent and pressure-supply passage in the casing or shell, and a vent and pressure-supply passage in the controlling-plug, each passage having its mouth elongated in the direction circumferentially of the plug for the ends of the mouth to overlap with the initial opening of the valve and admit pressure before the filling-passages for the liquid are opened, substantially as described.

4. In a filling-valve, the combination of a casing or shell, a controlling-plug entered into the casing or shell, a liquid-passage in the casing or shell and in the controlling-plug, a vent and pressure-supply passage in the casing or shell, a vent and pressure-supply passage in the controlling-plug, the two vent and pressure-supply passages opening for communication with the initial opening of the

valve and before the opening of the liquid-passage, a filling-tube communicating within the plug with the liquid-passage, and a vent tube or passage in the filling-tube in communication with the vent and pressure-supply passages for admitting pressure before admitting liquid to the filling-tube, substantially as described. 55

5. In a filling-valve, a casing or shell and a controlling-plug, both the casing or shell and the controlling-plug having a passage for liquid and a passage for supplying and venting pressure, the passage for the liquid and the passage for the pressure having a coacting relation for the pressure-passage to open before the liquid-passage opens thereby bottling the liquid under an equalized pressure, and a filling-tube in fixed relation to the plug, substantially as described. 70

6. In a filling-valve, a casing or shell and a controlling-plug, both the casing or shell and the controlling-plug having a passage for liquid and a passage for supplying and venting pressure, the passage for the liquid and the passage for the pressure arranged to have the pressure-passage first open admitting pressure to and equalizing the pressure in the bottle for bottling liquids under pressure, and a filling-tube having therein an air-passage and communicating within the plug with the passages therein, substantially as described. 80

7. In a filling-valve, a casing or shell and a controlling-plug, both the casing or shell and the controlling-plug having a passage for liquid and a passage for supplying and venting pressure, the passage for the liquid and the passage for the pressure arranged to have the pressure-passage first open admitting pressure to and equalizing the pressure in the bottle, in combination with a filling-tube in fixed relation with the plug and communicating within the plug with the liquid-passage, and a vent tube or passage in the filling-tube for bottling liquids under pressure, substantially as described. 95
